ATTORNEYS

UNITED STATES PATENT OFFICE.

GEORGE H. BLISS, OF MALDEN, MASSACHUSETTS, ASSIGNOR TO HELEN E. CUSHMAN,
OF MALDEN, MASSACHUSETTS.

COVER FOR BUTTER TUBS, ETC.

Application filed September 16, 1921. Serial No. 501,071.

To all whom it may concern:

Be it known that I, GEORGE H. BLISS, citizen of the United States, residing at Malden, in the county of Middlesex and State of 5 Massachusetts, have invented new and useful Improvements in Covers for Butter Tub, Etc., of which the following is a specification.

The object of this invention is to provide 10 a strong, durable and inexpensively constructed cover for butter tubs and other cylindrical receptacles, adapted to be securely attached to a receptacle and protect the latter and its contents against damage 15 when in transit or in storage.

The invention is embodied in the improvement hereinafter described and claimed.

Of the accompanying drawings forming a part of this specification,—

20 Figure 1 is a perspective view of my improved cover.

Figure 2 is a fragmentary section on line 2—2 of Fig. 1.

The same reference characters indicate the 25 same parts in all the figures.

In the drawings, 12 represents a disk preferably composed of wooden sections connected at their meeting edges by tongues and grooves or otherwise—the disk being adapted to be handled and turned during the 30 operation of securing thereto the sheet metal annulus, next described.

Said annulus is formed from a strip of sheet metal, preferably sheet iron, the width 35 of the strip being greater than the thickness of the disk.

In applying the strip, I mount the disk on a rotary holder or face plate, and attach one end of the strip to the disk by a fastener, 40 such as a nail 13 driven through a hole formed for its reception in the strip and into the margin of the disk, one edge of the strip projecting from the outer side and the opposite edge from the inner side of the disk, I then rotate the disk and wrap the strip around the margin thereof. At the same time, by suitable sheet metal working instrumentalities, I bend one edge of the strip inwardly and thus form a flange 14 45 which is seated on the outer side of the disk, and form between the edges of the strip a

bead 15 which projects inward under the margin of the under side of the disk. When the strip is completely wrapped around the margin of the disk its outer end is secured 55 to the disk by another fastener 16. The strip is thus converted into an annulus 17, one edge of which has the flange 14 seated on the outer side of the disk, the opposite edge projecting below the inner side of the disk and 60 forming an annular rim or flange which is stiffened by the bead 15 and is adapted to embrace the upper end of the butter tub or other receptacle.

The annulus may be provided with holes 65 18 to receive fasteners driven into the receptacle, and with holes 19 to receive fasteners driven into the margin of the disk. If desired, sheet metal strips 20 may be attached to the completed cover said strips being 70 adapted for attachment to the tub.

The length of the sheet metal strip is preferably greater than the diameter of the disk so that one of its ends overlaps the other as shown by Figure 1. 75

I claim:

1. A receptacle cover composed of a disk and a sheet metal annulus surrounding the disk and of greater width than the thickness of the latter, said annulus having at one 80 edge an inwardly turned flange seated on the outer side of the disk, and between its edges a circumferential bead projecting inwardly under the margin of the inner side of the disk so that the margin of the disk is confined between the flange and the bead, the annulus being formed from a strip attached to the disk.

2. A receptacle cover composed of a disk, a sheet metal strip wider than the thickness 90 of the disk, a fastener uniting one end of the strip to the disk, the strip being wrapped around the margin of the disk to form an annulus and having one of its edge portions bent to form a flange seated on the 95 outer side of the disk, and its intermediate portion beaded to engage the margin of the inner side of the disk, and a fastener uniting the opposite end of the strip to the disk.

In testimony whereof I have affixed my 100 signature.

GEORGE H. BLISS.
